UNITED STATES PATENT OFFICE.

HERMANN STADELmann, JR., OF APOLDA, GERMANY.

AUTOMATIC CAB-SIGNAL.

SPECIFICATION forming part of Letters Patent No. 651,674, dated June 12, 1900.

Application filed October 5, 1899. Serial No. 732,712. (No model.)

To all whom it may concern:

Be it known that I, HERMANN STADELmann, Jr., merchant, a subject of the Grand Duke of Saxe-Weimar, residing at Apolda, in the 5 Grand Duchy of Saxe-Weimar, German Empire, have invented certain new and useful Improvements in Switch-Point Safety-Checks for Engine-Drivers, of which the following is a specification.

10 My invention relates to improved means for automatically operating signal-indicators carried on a locomotive-engine to inform the engine-driver, when unable to see the usual signals clearly, more especially in rainy or 15 foggy weather and when at a sufficient distance ahead of the junction or switch, whether the switch-points to be passed are correctly set.

My invention consists in the hereinafter- 20 described mechanism for operating the signal-indicators both by an electric circuit and by mechanical means, so that in the event of failure of one of the two arrangements the other will operate the proper indicator, thus 25 affording absolute safety under all circumstances against any accidents arising from wrongly-set switch-points.

In the annexed drawings, illustrating the invention, Figure 1 shows in elevation one 30 form of the arrangement of safety-check signal-indicators on a locomotive with means operating said indicators, both electrically and mechanically, from devices located on the track and connected with the switch-points. 35 Fig. 2 is a plan of a portion of the rail-track with devices adjacent thereto for operating the signal-indicators on the locomotive. Fig. 3 is an enlarged view of a double set of signal-indicators, one set to be operated mechanically and the other electrically. Figs. 4 and 40 5 are views at right angles to each other illustrating an overhead arrangement of the mechanism for operating the signal-indicators both electrically and mechanically. Fig. 6 shows 45 in elevation and plan an arrangement for recording the indicators of the signals.

In a suitable part of the locomotive, well 50 in sight of the engine-driver, there are located as many numbered flaps or hinged indicators A as there are switch-rails or switch-points at any place to be passed and the position of which must be made known to the engine-

driver. In the drawings three of these indicators are shown in each set, corresponding with the number of switch-points shown. The numbers marked on these indicators A correspond exactly with the switch-rails and switch-points B, which on being set will act upon wedge-shaped catches D, that may be fitted to the track at a suitable distance in front of the 60 switch-points B, Fig. 2, and connected with the switch-points by means of draw-rods or wire-pulls C, preferably to be laid underground. These catches D are mounted on spindles V, placed at right angles to the rail-track S, and are as a rule held fast in a certain position by means of springs F. The catch D belonging to rail 1 is coupled with the catch D belonging to rail or point 2, while the further catches D are each fitted on a separate spindle, so that they can be shifted laterally on the latter and be held in position by a spring. (See Fig. 2.)

The locomotive in Fig. 1 is fitted underneath with bell-crank levers W, which can 75 turn on a transversely-arranged axis or spindle Q, but cannot be shifted laterally. These bell-crank levers W carry, each on its downwardly-projecting arm w, a gliding contact-roller R, and each arm w is formed with or 80 carries an upward-bent flat spring w'. These springs w' or levers W are adapted to be connected by an electric circuit with electromagnets G and from these with one pole of the battery P. The other pole of the battery is 85 connected with knobs t or their supports T, that are arranged adjacent to said levers. If now the lever-arm w, with the roller R or the spring w', is moved in the direction indicated by arrow I, (which movement will be caused 90 by the roller R or the arm w coming into contact with a properly-set catch D while the train is in motion,) an electric circuit will be made and an electromagnet G will be thereby energized.

The armatures x of the electromagnets G 95 form the locking bolts or latches of the indicator-flaps A, which as soon as the latches are withdrawn will spring up or outward under the action of their spring-hinges t. These 100 latches or armatures x, which are constantly held in a locked position by springs u, may also be released by mechanical means through being connected by draw-rods or wire-pulls

Z with the horizontal arms w^2 of the bell-crank levers W, (see Fig. 1;) but an arrangement may be made whereby separate indicators A are provided for the mechanical and the electrical operating devices, respectively. (See Fig. 3.) If now the arms w of the levers W, projecting downward under the engine, strike during the run of the train against properly-set catches D, the corresponding indicator-flaps A (in the example shown in Figs. 1 and 2 the indicator 1) will spring up, thus informing the engine-driver exactly what switch-points are set and whether they are set correctly. If a wrong indicator-flap A springs up, indicating a false position of the switch-points, the engine-driver will have sufficient time to stop the train, as this will take place about one thousand meters ahead of the junction.

20 A duplicate arrangement of signal-indicators may be provided to be operated by other track devices located farther along—say about fifty meters in front of the junction—thus insuring a fourfold check.

25 In order to provide for operating the signal-indicators A in the same manner as already described, in case the engine runs backward, the levers W are provided with arms w^3 , projecting backward (and which may be fitted with spring arrangement) and which, like the arms w^2 , are connected by rod or wire pulls Z with the armatures or latches x, and, like the arms w, serve at the same time as electric contacts, Fig. 1.

35 It will be obvious that the described signaling mechanism, electrical and mechanical, can be arranged for any number of switch-points.

40 Of course in place of the numbers on the indicator-flaps A signal-signs or any other marks or indications may be used.

45 As the catch arrangements D on the track might be blocked by ice or frost and as sometimes by reason of structural or other obstacles and difficulties it might be impossible to fit them up on the track or between the rails, there may be provided in such cases the arrangement illustrated in Figs. 4 and 5, wherein the catches or contact-pieces D are placed overhead, the corresponding contact-levers on the engine being arranged not underneath, but over the locomotive—that is, projecting upward—but of course care must be taken that these contact arrangements do not project beyond the prescribed carriage-gage or inside it to an excessive degree, lest other parts of the passing train should be damaged thereby.

60 As will be seen from Figs. 4 and 5, the locomotive contacts may be fitted to a frame H, supported on the locomotive, while the track contacts or catches D' are suspended above from a suitable pillar-bracket y. Of course the contact arrangements may also be fitted laterally, in which case ordinary posts or pillars will serve to carry the track contacts or catches D'.

In order to make a permanent record of every indication of the signaling or indicating devices fitted to the locomotive, so as to have a check on the engine-driver, a mechanical arrangement or other contrivance m, acting on a reel of paper i or the like, may be attached to an extension t of the hinge-pivot t of each indicator A, which arrangement will cause the reel of paper i to turn to a certain extent each time when the indicators A are released or the respective signal arrangements on the locomotive are set in action, a mark of some kind being made on the piece of paper tape 80 i^2 unwound, and which will be automatically rewound on a spring-reel i' . Such mark might be made, for instance, by a pin or pencil point a brought to bear against the paper by the indicators A when springing up. Of course any other registering arrangement or recording appliance may be used for this purpose.

What I claim as my invention is—

1. In signaling apparatus for railways, the combination with a switch-point, and a catch located at a distance from said switch-point and movable therewith, of signal mechanism carried on a locomotive and comprising a movable indicator, an electromagnet having its armature arranged as a latch for locking 95 said indicator, a bell-crank lever projecting from the locomotive and adapted to be engaged and rocked by the said catch that is movable with the switch-point, an electrical connection between said bell-crank lever and the electromagnet, a pull-rod mechanically connecting said bell-crank lever with the indicator-latch, an electric contact supported adjacent to said bell-crank lever, and a battery having one pole connected with said contact and its other pole connected with the electromagnet, whereby the indicator is released both mechanically and electrically, substantially as described.

2. In signaling apparatus for railways, the combination with a plurality of switch-points, and a plurality of catches located at a distance from said switch-points and each movable with its connected switch-point, of signal mechanism carried on a locomotive and comprising a plurality of movable indicators corresponding with the respective switch-points, electromagnets having their armatures arranged as latches for locking the several indicators, bell-crank levers projecting from the locomotive in position to be engaged and rocked by a properly-set catch connected with a switch-point, electrical connections between the several bell-crank levers and electromagnets, pull-rods mechanically connecting the several bell-crank levers and indicator-latches, electric contacts supported adjacent to the several bell-crank levers, and a battery having one pole connected with said contacts and its other pole connected with the electromagnets, substantially as and for the purpose described.

3. In signaling apparatus for railways, the combination with a plurality of switch-points,

and a plurality of catches located at a distance from said switch-points and each movable with its connected switch-point, of signal mechanism carried on a locomotive and comprising a plurality of indicators arranged in sets, electromagnets having their armatures arranged as latches for locking the indicators of one set, mechanically-operated latches for locking the indicators of another set, bell-crank levers projecting in position to be engaged and rocked by a properly-set catch connected with a switch-point, electrical connections between the several bell-crank levers and electromagnets, pull-rods connecting the

said bell-crank levers with the mechanically-operated indicator-latches, electric contacts supported adjacent to the several bell-crank levers, and a battery having one pole connected with said contacts and its other pole connected with the electromagnets, substantially as and for the purpose described. 15

In testimony whereof I have hereunto set my hand in presence of two subscribing witnesses.
